UNITED STATES PATENT OFFICE.

NORBERT CHARLES DEIGHAN, OF CLEVELAND, OHIO.

ADVERTISING APPARATUS.

Application filed May 12, 1923. Serial No. 638,526.

To all whom it may concern:

Be it known that I, NORBERT CHARLES DEIGHAN, a citizen of the United States, and a resident of Cleveland, county of Cuyahoga, State of Ohio, have invented certain new and useful Improvements in Advertising Apparatus, of which the following is a specification.

This invention relates to advertising apparatus and more particularly to apparatus especially adapted for outdoor advertising, although not limited to such use.

It is one of the objects of the invention to provide advertising apparatus comprising movable scenery representing a landscape or equivalent scenery with space thereon to be traversed by a vehicle of some sort and means for giving such movements to the scenery and to the vehicle as will produce the illusion of the vehicle traversing the space.

Another object of the invention is to provide apparatus of the kind referred to adapted for installation in relatively large units and also for continuous operation by comparatively simple means and, when desired, to be visible from different streets, as when located on a space between two parallel streets.

Other objects and the features of novelty will be apparent from the following description taken in connection with the accompanying drawings, of which:

Figure 1 is a front elevation of an advertising sign embodying my invention, with parts broken away to show some of the operating mechanism;

Fig. 2 is a horizontal section taken on the line 2—2 of Fig. 1;

Fig. 3 is an enlarged section on the line 3—3 of Fig. 1;

Fig. 4 is a view of the parts shown in Fig. 3 as they appear from the line 4—4 of that figure.

Fig. 5 is an enlarged fragment of Fig. 1 with parts shown in section;

Fig. 6 is a detail section on the line 6—6 of Fig. 5; and

Fig. 7 is an enlarged fragmentary section on the line 7—7 of Fig. 1.

Referring to the drawings, 10 indicates a suitable frame supported on a suitable foundation indicated at the points 11, 12 and 13. This frame is preferably of a decorative nature, as indicated in Fig. 1, and is provided with an opening 14 through which

the display parts of the apparatus may be viewed. The frame 10 may be of any length desired and I contemplate embodying the invention in constructions of various sizes from a small apparatus suitable for display in a store window up to apparatus having a length of fifty or more feet and of different widths depending upon the location of the apparatus and the number of sides from which it is desired that the display portions thereof shall be visible. In Fig. 2 I have indicated a rectangular frame 10 such as would be suitable for exhibiting the display portion of the apparatus on four sides and I have indicated the various openings on the four sides by the numeral 14. Apparatus such as indicated in Fig. 2 can be made in any length desired and is suitable for installation on a vacant lot between two parallel streets from which the sides 15 and 16, respectively, may be viewed, and the ends 17 and 18 viewed by people approaching from either direction on said streets or from a cross street in case the sign is located on a corner property.

The display apparatus consists of a suitable fabric 19 hung vertically and preferably in the form of an endless belt passing around long rollers or pulleys 20, 21, 22 and 23. In Fig. 2 I have indicated the fabric 19 as passing from the roller or pulley 23 around a roller or pulley 24 and thence in zigzag formation around a series of rollers or pulleys 25 to the roller or pulley 26 whence the fabric passes to the roller 20. It will be understood that the fabric may, if desired, pass directly from the roller or pulley 23 to the roller or pulley 20, where a comparatively short scene, which is frequently repeated, in the operation of the device, is suitable. However, when it is desired to have a comparatively long scene that is repeated, in the operation of the device, at relatively long intervals, I prefer to use the zigzag formation above described. Painted on or otherwise applied to the fabric 19 is suitable scenery preferably representing a landscape or a water scene or other space to be traversed by some form of vehicle. Advertisements may be arranged on the scenery as illustrated in Fig. 1. This scenery is so arranged as to be visible through the various openings 14 and, in order to move the fabric, I provide an electric motor 27 or other suitable power device which may be operatively connected with the pulley 21 by suitable

gearing 28, or in any other preferred manner.

In order to support the fabric 19 and to properly move it, I arrange along its upper and lower edges suitable chains 29 and 30, respectively. These chains are secured to the edges of the fabric at frequent intervals and run around suitable sprockets on the various rollers or pulleys on which the fabric 19 runs.

In order to support the upper edge of the fabric 19 and prevent sagging I use any suitable device such as the sprockets 31 which are rotatably arranged on the vertically arranged shafts 32, the latter being preferably supported from the frame 10 by a hinge connection 33, as indicated in Fig. 7. A tension spring 34 tends to draw the sprocket 31 toward the plane of the fabric 19 and therefore maintains the sprocket in engagement with the chain 30. In order to back up the chain 30, adjacent the sprockets 31, I use a pair of sprockets 35 arranged on opposite sides of the sprocket 31 and carried by a suitable bracket 36. From Figs. 2 and 7 it will be apparent that the device described will, when placed at frequent intervals along the chain 30, support the fabric 19 and maintain it in its proper position.

Referring to Fig. 1, it will be observed that I have indicated, as a part of the scenery on the fabric 19, a highway at 37 and a railroad track at 38. Supported in front of the fabric 19 in a relatively stationary position, is a representation of an automobile 39, this representation being carried by the brackets 40 (see Figs. 3 and 4) in such relation to the scenery as to produce the illusion of an automobile on the highway 37. In order to give "life" to the scene the wheels 41 of the automobile may, in an apparatus for outdoor display, be of substantially natural size and equipped with real tires and be connected with the representation 39 by springs 42 which will allow the wheels to move up and down in the same way that automobile wheels move in traversing a highway. The wheels 41 are rotatably mounted and run on an endless chain 43 which is arranged just below the opening 14. The chain 43 carries lugs 44 at frequent intervals and when these lugs pass under the wheels 41 the latter are raised and lowered to give the effect of passing over a bump in the road. The chain 43 is carried on suitable sprockets 45 and one of the sprockets 45 has connected therewith a pulley 46 over which an endless belt 47 passes. The belt 47 also passes over a pulley 48 which is keyed to the shaft 49 and a pulley 50 is also keyed to this shaft and driven by a belt 51 from a pulley 52 on the roller or pulley 20 so that the chain 43 will be driven in timed relation to the fabric 19.

In order to give the illusion of a moving

train the track 38 is preferably made of a flexible material such as rubber and secured to the face of the fabric 19 in such manner as to indicate grades and curves in the railroad. The representation of a train is indicated at 53 and consists of a locomotive and several cars, coupled together.

The smoke from the locomotive is represented at 54 and extends to a point behind the frame 10 where it is pivotally connected with a suitable supporting bracket 55. The wheels 54' of the locomotive and the cars are preferably grooved so as to run on the track 38 and from the drawings, and particularly Figs. 1, 5 and 6, it will be apparent that the movement of the fabric 19, with the scenery thereon, will produce the illusion of a train running along the track 38.

While I have illustrated, in connection with the movable scenery merely an automobile and a train, it will be understood that the invention is not limited to these devices and that other forms of vehicles and other scenes may be utilized for the purpose of giving "life" to the apparatus. I, therefore, contemplate in the claims, that the terms "vehicle" and "space to be traversed by the vehicle" shall include different forms of vehicles and the space to be traversed by each.

Having thus described my invention, what I claim is:

1. In apparatus of the class described, the combination of a frame, a movable fabric supported on said frame and having scenery thereon representing space to be traversed by a vehicle, a representation of a vehicle supported in front of said scenery, means for moving said fabric in a direction to give the illusion of said vehicle traversing said space, and means on said fabric engaged by said vehicle and arranged to produce movements in said vehicle in a plane parallel to the plane of the adjacent portion of said fabric.

2. In apparatus of the class described, the combination of a frame, vertically arranged shafts in said frame, an endless fabric arranged on said shafts, relatively fixed means for supporting said fabric intermediate said shafts to prevent sagging of the fabric, said fabric having scenery thereon representing space to be traversed by a vehicle, a representation of a vehicle supported in front of said scenery, by means invisible from outside the apparatus, in position to produce the illusion of traversing said space, and means on said fabric cooperating with said representation of a vehicle to produce movements thereof.

3. In apparatus of the class described, the combination of a frame, vertically arranged shafts in said frame, an endless fabric arranged on said shafts, relatively fixed means for supporting said fabric intermediate said

shafts to prevent sagging of the fabric, said fabric having scenery thereon representing space to be traversed by a vehicle, a representation of a vehicle supported in front of
5 said scenery, by means invisible from outside the apparatus, in position to produce the illusion of traversing said space, flexible

guiding means secured on said fabric, and means on said representation of a vehicle engaging said guiding means to produce 10 vertical movements in the vehicle.

In testimony whereof I affix my signature.

NORBERT CHARLES DEIGHAN.
